UNITED STATES PATENT OFFICE

156,196

DESIGN FOR A PORTABLE WASHING MACHINE UNIT

Arthur T. Britton, Mountain View, Calif.

Application July 23, 1947, Serial No. 140,466

Term of patent 14 years

(Cl. D49—1)

To all whom it may concern:

Be it known that I, Arthur T. Britton, a citizen of the United States, residing at Mountain View, in the county of Santa Clara and State of California, have invented a new, original, and ornamental Design for a Portable Washing Machine Unit, of which the following is a specification, reference being had to the accompanying drawing, forming part thereof.

Figure 1 is a perspective view of a portable washing machine unit, showing my new design;

Figure 2 is a top plan view thereof;

Figure 3 is a right hand end view of Fig. 1.

The dominant features of my design reside in those portions shown in full lines, the fragmen-

tary top of a conventional wash tub is shown in broken lines for illustrative purposes only.

I claim:

The ornamental design for a portable washing machine unit, as shown and described.

ARTHUR T. BRITTON.
